TUBULAR FOLDABLE FRAME
Orman M. Rainwater, 2551 Midvale Ave.,
Los Angeles, Calif.
Filed Jan. 16, 1962, Ser. No. 166,603
6 Claims. (Cl. 108—129)

This invention relates to tubular foldable frames for furniture, stands, and the like, and particularly to a table or stand composed of simple telescoping U-shaped units with a top.

Folding furniture using tubular frames is well known, the present invention using basic units of four U-shaped tubes, the ends of which may be telescoped and folded to provide a flat package for easy transporting and storage. The four tubular units may be used independently as a frame or a table top and may be placed on the top cross-sections of the units, the table top being hinged to one cross-section to permit the tubular sections to be folded flat against the table top. The table or stand, therefore, becomes extremely simple to erect and fold after use.

By the use of interconnecting couplings, the table may be adjusted to different heights and a shelf provided under the table top. Furthermore, a seat may be easily attached to the frame by simply connecting two U-shaped units to extending lugs between the telescoping members.

The principal object of the invention, therefore, is to facilitate the erecting and folding of a table or stand.

Another object of the invention is to provide an improved tubular telescoping table or stand.

A still further object of the invention is to provide a table or stand using U-shaped tubular members which telescope and fold.

A better understanding of the invention may be had from the following detailed description when read in conjunction with the accompanying drawings, in which:

FIG. 1 is a perspective view of a table embodying the invention;

FIG. 2 is a perspective view showing two positions of the foldable members;

FIG. 3 is a perspective view showing another position of the foldable members during the folding operation;

FIG. 4 is a perspective view showing the table in fully folded position;

FIG. 5 is a detail view showing one manner of holding the telescoping members in fixed position and taken along the line 5—5 of FIG. 1;

FIG. 6 is a detail view of the attachment of the cross tubular sections of the units to the table top and taken along the line 6—6 of FIG. 1;

FIG. 7 is a perspective view showing interconnecting units of the tubular members to provide a table shelf;

FIG. 8 is a detail view of one type of interconnecting unit embodied in the invention and taken along the line 8—8 of FIG. 7;

FIG. 9 is a perspective view showing a bracing structure for the frame;

FIG. 10 is a perspective view showing a seat attachment for the table;

FIG. 11 is a detail view taken along the line 11—11 of FIG. 9; and

FIG. 12 is a detail view showing another type of interconnecting unit for the tubular members of the invention.

Referring to the drawings in which the same reference numerals identify the same elements, a table top 5 is provided with two cleats or struts 6 and 7, the ends of the cleats being at an angle as shown in FIG. 6. The frame is composed of four U-shaped basic tubular units. The unit to which the top 5 is hinged has a section 16

2

interconnecting leg sections 16a and 16b. A similar unit has a section 18 interconnecting leg sections 18a and 18b. One leg unit has a section 12 interconnecting leg sections 12a and 12b, leg section 16b telescoping into leg section 12a, and leg section 18a telescoping into leg section 12b. The fourth unit has a section 14 interconnecting leg sections 14a and 14b, leg section 18b telescoping into leg section 14a, and leg section 16a telescoping into leg section 14b. The units 16, 16a and 16b and 18, 18a and 18b may be raised and lowered to vary the table height, as shown by the broken lines 12c and 14c. To hold the four units in any adjusted fixed position, the vertical sections of the units are provided with holes such as shown at 8 in FIG. 5, through which a thumb nut 9 may be threaded. Any other suitable means for locking the leg sections in position could be used.

The two cleats 6 and 7 are hinged to the cross-section 16 of units 16, 16a, and 16b, as shown in detail in FIG. 6, the hinge being composed of a right angle plate 10 which extends over the horizontal section 16 and is attached to the cleat by screws such as shown at 11. The other section 18 is held in place by the spring or resiliency of the units which causes section 18 to abut the sloping edges of the cleats 6 and 7.

As shown in FIG. 1, the table is in one fixed elevated position and reference is now made to FIGS. 2, 3, and 4 to illustrate the manner of folding the U-shaped telescoping tubing. As shown in FIG. 2, the unit 12, 12a and 12b is rotated to the left when the section 18 is removed from the notches at the ends of the cleats 6 and 7. By corresponding numbers, it will be noted that the unit 12, 12a and 12b rotates on leg 16b of unit 16, 16a and 16b, and unit 14, 14a and 14b rotates on leg 16a of unit 16, 16a and 16b. Thus, the unit 14, 14a and 14b and the unit 12, 12a and 12b will rotate until they become in substantially the same place as unit 16, 16a and 16b, as shown in FIG. 2.

The next position in the folding operation is shown in FIG. 3 where the unit 14, 14a and 14b is rotated over unit 12, 12a and 12b until the two units are in substantially parallel planes, after which the sections are folded at right angles on the hinges 10 until the units are flat with the table top 5, as shown in FIG. 4. To unfold the table, it will be only necessary to reverse the folding operation.

Referring, now, to FIG. 7, a similar unit is illustrated wherein the cross cleats 25 and 26 of a top 27 are hinged by hinges 31 to a cross-section 28 of a U-shaped unit having vertical sections 29 and 30. A similar unit is shown at 32, 33, and 34. Two similar U-shaped units are shown at 36, 37, and 38 and at 40, 41, and 42. In this modification, the upper and lower U-shaped sections are joined by cylindrical couplings 44 having extensions 45. In FIG. 8, the leg section 38 is shown accommodating an end 47, and leg section 33 is shown accommodating an end 48 of the coupling 44. The cylindrical section of the coupling 44 will, therefore, abut the end of the tubular section 38, while the end of tubular section 33 will abut the cylindrical portion of the coupling 44. With the extensions 45 rotated to extend toward the center of the table top 27, a shelf 50 may be mounted thereon. If desired, the cylindrical portion of the coupling 44 could be tubular to permit the leg 33 to telescope therethrough for adjusting the height of the table, a set screw being provided to hold the legs in fixed position.

In FIG. 9, a table top 52 has cleats 53 and 54 and U-shaped members similar to FIG. 7, which are interconnected by brace members 55 and 56, the construction of the brace members being shown in cross-section in FIG. 11. The braces 55 and 56 consist of tubes 58 and 59 in the ends of which is a resilient rubber rod 61 which

3

will permit the braces to bend when the rigid sleeve 62 is removed therefrom, as shown in FIG. 9. The ends of the tubes 58 and 59 can be mounted on pin extensions 45, as shown in FIG. 8, or on pin extensions 64 attached to a collar 65 having a wing set screw 66, as shown in FIG. 12, which is a modification of the coupling between units, as shown in FIG. 8. The braces 55 and 56 may also form a support for a shelf, a portion of which is shown at 67.

Referring, now, to FIG. 10, a seat is provided for the table made up of the tubing units just described, a portion of such a table being shown by the top 70 and sections 71, 72, 73, 74 and 75. The seat is made up of two U-shaped sections 77, 78, 79 and 81, 82, 83, the sections 78 and 82 being strapped together by straps 85 and 86. A seat 88 may be attached to the unit 81, 82 and 83 in any suitable manner, the two U-shaped units being held in position by braces 90 and 91. The ends of sections 81 and 83 of this U-shaped unit are attached to extensions such as 45 or 64, shown in FIGS. 8 and 12, respectively, and held in position thereon by set screws 93 and 94. Thus, to remove the seat, it is only necessary to loosen the set screws 93 and 94, break the braces 90 and 91, and rotate the unit 73, 74 and 75 and unit 77, 78, and 79, to fold the seat on the straps 85 and 86.

The construction described above provides a particularly simple frame structure for a table or stand which may be rapidly erected and folded into a minimum of space. Since it involves only four basic units of similar form and construction, it is economical to manufacture.

I claim:

1. A folding table comprising a plurality of U-shaped tubular units, each unit having two leg sections and a section interconnecting one end of each of said leg sections, the leg sections of one of said units telescoping within a respective leg section of two other units, and within the leg sections of another unit telescoping within the leg sections of two other units, one of said other leg sections of said two other units and said first-mentioned unit being adapted to rotate about the leg sections of said other units to first fold said units into substantially a single plane and then to continue said rotating to fold said units into two substantially parallel planes, a table top being provided with parallel cleats along two opposite edge portions of said top, one of said cleats being hinged to one interconnecting section of one of said U-shaped units, the other cross member being resiliently attached to said other cleat.

2. A foldable telescoping table frame comprising four U-shaped tubular units, each unit having two parallel leg sections and a section interconnecting one end of each of said leg sections, two of said units having their internal leg diameters of substantially the same size as the external leg diameters of the other two units and adapted to be telescoped therein, the two legs of each one of said units having the smaller diameter legs extending into one leg of each of said other units to form a rectangular supporting frame, two of said units being rotatable on the smaller diameter leg sections of said other units to first permit the folding of said units into substantially a single plane and then to fold said units into two substantially parallel planes, a table top having a pair of parallel sup-

porting cleats on one side thereof mounted on the interconnecting sections of two of said units, one of said cleats being pivotally connected to one of said interconnecting sections and said other cleat being resiliently connected to said other interconnecting section.

5 3. A foldable telescoping table frame in accordance with claim 2 in which the legs of said units are joined by couplings having extensions therefrom to support a shelf.

4. A foldable telescoping table frame in accordance with claim 3 in which braces are provided, each two of said couplings being joined by said braces, said braces including a flexible core and interconnected tubes, and a tube sleeve for interconnecting said tubes.

5. A foldable telescoping table frame in accordance with claim 3 in which a pair of U-shaped tubular units is pivotally interconnected at their cross sections, a seat being mounted on one unit, said unit having said seat thereon having the ends of its legs connected to two of said couplings.

20 6. A table or stand structure having four tubular U-shaped units and a top, each of said units having two leg sections and a section interconnecting one end of each of said leg sections, two of said units having leg sections 25 of a smaller external diameter than the internal diameter of the leg sections of said other units, said top being supported by the interconnecting members of two of said units, said structure being erected by inserting one smaller diameter leg section of a first unit into a larger diameter leg section of a second unit, the other smaller diameter leg section of said first unit being inserted in the larger diameter leg section of a third unit, and inserting one smaller diameter leg section of a fourth unit into the other larger diameter leg section of said second unit and the other smaller diameter leg section of said fourth unit into the other larger diameter leg section of said third unit, two of said units being rotatable on two of said leg sections thereof and two other units being rotatable on two of said leg sections of said other units to a position in one plane and said first-mentioned two units being further rotatable on their leg sections to position all of said units in two substantially parallel planes, said top having a pair of parallel edge portions thereof, one of said cleats being hinged to one of said supporting interconnecting members, and said other cleat being resiliently attached to said other supporting interconnecting member.
